[57] CLAIM

The ornamental design for a rotary actuator for a damper, as shown.

DESCRIPTION

FIG. 1 is a perspective view of a rotary actuator for a damper, showing my new design;

FIG. 2 is an enlarged top plan view thereof; FIGS. 3 and 4 are, respectively, enlarged end elevational views thereof;

FIG. 5 is an enlarged bottom plan view thereof; and FIGS. 6 and 7 are, respectively, enlarged front and rear elevational views thereof.
